UNITED STATES PATENT OFFICE.

ANGELO PERRI, OF WATERTOWN, MASSACHUSETTS, ASSIGNOR TO REECE SHOE MACHINERY COMPANY, OF BOSTON, MASSACHUSETTS, A CORPORATION OF MAINE.

METHOD OF WIRING OR BINDING THE ENDS OF LASTED BOOTS AND SHOES.

1,237,549.

Specification of Letters Patent. Patented Aug. 21, 1917.

Application filed April 4, 1917. Serial No. 159,747.

To all whom it may concern:

Be it known that I, ANGELO PERRI, a citizen of the United States of America, and a resident of Watertown, in the county of 5 Middlesex and Commonwealth of Massachusetts, have invented certain new and useful Improvements in Methods of Wiring or Binding the Ends of Lasted Boots and Shoes, of which the following is a specification.

10

This invention relates to the method of wiring or binding the ends of boots and shoes after the same have been wiped or lasted, and applies particularly to the toe end of the shoe. An object of this invention is to provide means to rapidly secure and retain the upper on the last at the toe or fore part of a boot or shoe in the stretched condition in which it is left after undergoing the wiping or lasting operation, whether the said operation is done by hand or machine.

It is a further object of this invention to provide a common fastening means for the 25 two ends of the binding wire other than the usual tacks or fastening devices employed to temporarily hold the upper to the last at the fore part thereof.

Another object of the invention is to facilitate the removal of the wire or binder, which removal is necessary when operations subsequent to the lasting operations are to be performed upon the shoe, such for instance, as sewing the welt to the upper in 35 making a welt shoe, the removal of the wire being rapidly accomplished upon the dislodgment of the common fastening means employed to which both ends of the wire are secured in usual manner.

40 Another and important object of the invention is to reinforce and virtually lock against movement the tacks or fastening devices employed to temporarily hold the upper to the last at the fore part, which are under considerable strain, due to the tendency of the upper, through which the tacks 45 pass, to resume its normal condition after being stretched over the last.

Other objects of the invention will be further pointed out in the specification and the claims hereinafter given.

Of the drawings:

Figure 1 represents in bottom plan view the toe or fore part of a boot or shoe after

having passed through the wiping or lasting 55 operation and in condition to receive the wire or binder which is indicated thereon, and

Fig. 2 represents a section on the line 2-2, Fig. 1, looking in the direction of the 60 arrow.

Similar characters designate like parts throughout the drawings.

Prior to the operation of end wiping or lasting a shoe the upper 10 is assembled and 65 placed upon a last 11 of the desired size and shape which has temporarily fastened thereto an innersole 12. The heel portion is then temporarily attached to the last and thereafter the operator pulls over the fore 70 part, stretching that portion sufficiently to eliminate wrinkles and properly position the upper with relation to the last.

In the wiping or lasting process, anchor tacks are used to hold the upper as indicated 75 at 13 and 14 in the drawings. The shoe is now ready for end lasting which may be done either by hand or machine, after which the wiped-in overlying portion of the upper 15 will be bound in preferably by means 80 of a soft or pliable wire 16.

When the wiping or lasting is done by machine, such for instance as the well-known bed laster, the wiper plates, after performing the function of wiping in the edge of 85 the upper, will be allowed to press upon the wiped-in edge of the upper to hold it in position against the inner sole while the operator is preparing to apply the binder cord or wire to the shoe at the fore part to 90 retain it in lasted position. The anchor tacks 13 and 14 above referred to offer the only means to which the wire may be secured, and hence one end of the wire will be wrapped one or more times around the 95 tack 13 and the free part of the wire will be led around the toe between the wiper plates and the shoe to the tack 14. Before securing the wire to the tack 14 the wiper plates will be raised slightly and the wire 100 will be drawn or pulled tightly into binding contact with the now upturned edge of the wiped-in portion of the upper 15, and when the wire has been pulled sufficiently 105 to prevent slippage of the wiped-in portion the wire is then given one or more turns around the tack 14.

The above briefly described method is one

at present in use and while it gives fair satisfaction it is not the ideal method by which the best results are obtained, nor does it facilitate the rapid removal of the 5 binder wire when said binder wire is to be removed to permit of subsequent operations on the shoe. The anchor tacks 13 and 14 must be quite firmly driven into the last in order to withstand the strain of the 10 stretched leather, as well as to remain immovable under the additional strain of the binder wire or cord, the ends of which are fastened or secured to them.

The tendency of the said tacks 13 and 14 15 is to yield outwardly or in the direction of pull of the leather causing a complete dislodgment or a bending of the tacks, either of which occurrences would act detrimentally to the work. In the event of a complete 20 dislodgement of a tack the operator would readily notice the trouble and would remedy it by repulling and relasting the shoe, but in the event of a bent tack caused by the 25 strain of the upper or wire, the work might progress without the operator observing the fault, and in this instance the upper would 30 creep or recede from the stretched condition in which it is left by the pulling over and lasting operations and would not properly or smoothly hug the last.

The present invention contemplates the elimination of the above-described faults and by reason of its simplicity greatly facilitates the operation of applying the 35 binder to the shoe as well as removing it therefrom when required to do so for subsequent operations upon the shoe.

As previously explained the assembled upper is temporarily attached to the last, 40 and the toe or fore part is stretched over and secured to the inner sole and last by means of the tacks 13 and 14, and preferably these tacks are driven in at an angle, as indicated in Fig. 2 of the drawings, the 45 reason for which will be hereinafter explained.

The fore part of the shoe will now undergo the lasting process either by hand or machine, and when that has been completed 50 the said toe part is ready to receive the binder or wire 16. The operator will now drive a tack 17 into the inner sole and last at a point approximately midway between the anchor tacks 13 and 14. Said tack 17 is intended 55 to serve as a common fastening means for the ends of the binder or wire, both ends of which will be wrapped around or otherwise secured to the said tack 17 when the binding operation is completed. If preferred, 60 this common fastening device might be used in conjunction with a hold down plate as a part thereof, such as is shown in patent to Snow, #568,463, issued Sept. 29, 1896, or in fact any means, preferably a single device 65 could be used in lieu of the tack 17 which

would suffice to accomplish the desired purpose. The operator will now secure one end of the binder or wire to the tack 17 and will carry the free portion around the anchor tack 13, thence around the gathered 70 portion of the wiped-in or lasted upper 15, and pull it taut to closely confine the said gathered portion between the wire and the shoulder 18 formed by the upturned channel lip 19. The wire will now be led around 75 the tack 14, and its end will be finally secured to the tack 17, as indicated in dotted lines in Fig. 1.

The object in driving the tacks 13 and 14 into the last at the angle shown will now 80 be apparent. By fastening the two ends of the wire 16 to the common fastening or tack 17, it will be readily seen that the pull of the wire 16 exerted on the anchor tacks 13 and 14 will serve to reinforce them 85 against the tendency of the stretched upper to pull the said tacks in the opposite direction. In fact, when the wire is passed around the said tacks and the gathered 90 parts of the upper and tightly pulled before finally fastening it, the tendency will be to straighten the said tacks 13 and 14, and by so doing will further stretch the upper at those points and will not allow it 95 to recede as would be the case if the said tacks were not virtually locked from outward movement in the novel manner employed in this invention.

This invention is intended to include in its scope any method of wiring or binding in 100 the gathered portions of the lasted toe or fore part of a shoe wherein the binder of whatever material starts at a given point as at 17 and after passing around the portion to be bound, finishes at and is secured to the 105 starting point. It is obvious that the starting and finishing point might be at either side of the shoe as at 13 or 14, or in fact at any convenient point, but in practice it has been found advisable and very convenient to 110 locate the said fastening device at a point intermediate the inturned edges of the upper.

It is usual to allow the wire or binding to 115 remain on the shoe until the wiped-in edge has set, after which, or just before subsequent operations are to be performed on the shoe, as for instance, welt attaching, the wire will preferably be removed therefrom. The use of a single device to which both 120 ends of the wire 16 are attached enables the operator with a single operation to quickly remove the said wire from the shoe by dislodging the said fastening device from its position, carrying with it the wire 16 which 125 will readily free itself from the tacks 13 and 14 and from the gathered edge of the upper 15.

The method at present in use and previously described herein, required the op- 130

erator to remove both the tacks 13 and 14 in order to free the shoe from the wire, and other tacks had to be inserted in their places to prevent the accidental displacement of the pulled and lasted upper on the last, 5 prior to any subsequent operation on the shoe such as the attaching of the welt.

In practice this invention has been found to be of great utility in retaining the lasted 10 portions of a shoe in the condition in which it was left by the lasting tools, and furthermore it has been found to be a time-saving method as well, as the wire may be removed by a single operation and there is no necessity of removing the anchor tacks 13, 14 15 and replacing them with others.

It is believed that the operation and advantages of this invention will be fully understood from the foregoing description.

Having thus described my invention, I 20 claim:

1. The method of binding the lasted ends of boots and shoes consisting in passing a flexible binder around the parts to be bound; 25 passing the ends of said binder around guide members adjacent said parts; and securing both ends of said binder to a member projecting from said last.

2. The method of binding the pulled and 30 lasted ends of boots and shoes, consisting in passing a flexible binder around the parts to be bound; passing the ends of said binder around guide members adjacent said parts; and securing the ends of said binder at a 35 point intermediate said guide members.

3. The method of binding the pulled and 40 lasted ends of boots and shoes, consisting in passing a flexible binder around the parts to be bound; securing the upper to the last by devices adapted to act as guide members for said binder; and securing the ends of said

binder to an anchor intermediate the guide members.

4. The method of binding the pulled and lasted ends of boots and shoes, consisting in 45 passing a flexible binder around the parts to be bound; passing the binder around devices temporarily used for securing the upper to the last; and securing the ends of said binder to an anchor whereby the said binder will be retained in locked position. 50

5. The method of binding the pulled and lasted ends of boots and shoes, consisting in 55 passing a flexible binder around the portion to be bound; and attaching the ends of said binder to a single securing means comprising a tack.

6. The method of binding the ends of lasted boots and shoes, consisting in passing a flexible binder around anchor tacks adapted to hold the fore part of the upper in stretched position; and around the portion of the upper to be bound; and securing the ends of said binder to a member located intermediate said tacks whereby the displacement of the anchor tacks by the strain of the 60 leather is prevented. 65

7. The method of binding the lasted ends of boots and shoes, consisting in fastening one end of a binder at a convenient point in 70 the fore part of a last; passing said binder around an upper-retaining tack near one edge of the last, around the gathered lasted portion of the upper, and around another of said upper-retaining tacks near the opposite 75 edge of said last, then directly toward and around the fastening point for the first mentioned end of the said binder.

Signed by me at Boston, Mass., this 30th day of March, 1917.

ANGELO PERRI.
